UNITED STATES PATENT OFFICE

151,075

DESIGN FOR A HANDBAG OR SIMILAR ARTICLE

Dorris M. Scott and Evelyn Steinberg, Los Angeles, Calif., assignors to Anita-Gay Creations, Inc., Los Angeles, Calif., a corporation of California

Application December 29, 1947, Serial No. 143,394

Term of patent 14 years

(Cl. D87--3)

To all whom it may concern:

Be it known that we, Dorris M. Scott and Evelyn Steinberg, both citizens of the United States, residing at Los Angeles, in the county of Los Angeles and State of California, have invented a new, original, and ornamental Design for a Handbag or Similar Article, of which the following is a specification, reference being had to the accompanying drawing, forming part thereof.

Fig. 1 is a front elevational view of a handbag or similar article, showing our new design.

Figs. 2 and 3 are rear and side elevational views, respectively, of the same.

Figs. 4 and 5 are top and bottom plan views, respectively, of the handbag or similar article.

We claim:

The ornamental design for a handbag or similar article, as shown.

DORRIS M. SCOTT.
EVELYN STEINBERG.
